UNITED STATES PATENT OFFICE.

ALBERT DATZ, OF JERSEY CITY, NEW JERSEY.

DESIGN FOR A PAPER-BOX BLANK.

SPECIFICATION forming part of Design No. 29,593, dated November 1, 1898.

Application filed October 4, 1898. Serial No. 692,649. Term of patent 31 years.

To all whom it may concern:

Be it known that I, ALBERT DATZ, a citizen of the United States, residing at Jersey City, in the county of Hudson and State of New Jersey, have invented and produced a new and original Design for a Paper-Box Blank, of which the following is a specification, reference being had to the accompanying drawing, forming part thereof, and which represents a face view of a paper-box blank incorporating my design.

The leading feature of my design consists of the new and original form and configuration of the blank, substantially as shown and described.

In the drawing, A designates the rectangular bottom section of the blank; B B, the

truncated cone-shaped side sections thereof; C, the rectangular top section; D D, the end portions of the bottom section A; E E and 20 F F, the end portions of the side sections B B, and G the securing-flap section, as shown.

What I claim is—

The design for a paper-box blank, substantially as shown and described.

Signed at Jersey City, in the county of Hudson and State of New Jersey, this 1st day of October, 1898.

ALBERT DATZ.
